(57) **CLAIM**

The ornamental design for a carrier for containers, as shown and described.

DESCRIPTION

FIG. 1 is a perspective view of a carrier for containers showing our new design, shown in a position of use with exemplary containers.

FIG. 2 is a left elevation view of the carrier for containers of FIG. 1, the right elevation view is a mirror image.

FIG. 3 is a front elevation view of the carrier for containers of FIG. 1, the rear elevation view is a mirror image.

FIG. 4 is a top plan view of the carrier for containers of FIG. 1.

FIG. 5 is a bottom plan view of the carrier for containers of FIG. 1; and,

FIG. 6 is a plan view thereof, shown independent of the exemplary containers to show aspects of the design not visible when combined, and further in an unfolded configuration.

The evenly-spaced broken lines in the drawings illustrate parts of the article that form no part of the claim as well as environmental subject matter of exemplary containers. None of the broken lines form part of the claimed design.
